T. SEVERSON

BUNGHOLE SPUD

Filed Sept. 18, 1922

Inventor

Thomas Severson.

Thomas Severson

Attorney

UNITED STATES PATENT OFFICE.

THOMAS SEVERSON, OF DULUTH, MINNESOTA; JAMES W. WALKER, OF DULUTH, MINNESOTA, ADMINISTRATOR OF SAID THOMAS SEVERSON, DECEASED.

BUNGHOLE SPUD.

Application filed September 18, 1922. Serial No. 588,953.

To all whom it may concern:

Be it known that I, THOMAS SEVERSON, a citizen of the United States, residing at Duluth, in the county of St. Louis and State of Minnesota, have invented certain new and useful Improvements in Bunghole Spuds, of which the following is a specification, reference being had therein to the accompanying drawing.

10 This invention relates to bunghole spuds for metal receptacles such as oil barrels, drums, or the like, and the principal object of same is to provide a more practical and efficient spud than heretofore known.

15 Other objects and advantages of the peculiar structure will appear in the further description of the invention.

Referring to the accompanying drawing forming part of this application in which 20 like reference characters indicate like parts:

Figure 1 is a plan view of a fragmental portion of a metal cask or barrel illustrating a plug and spud within same, and

Figure 2 is a central vertical section on the line 2—2 Figure 1.

1 represents the shell or skin of a metal receptacle, such as a drum or barrel, the rim of the bunghole of which is pressed outwardly preferably in polygonal form, as at 2, 30 such form being particularly for the purpose of preventing the possibility of rotation of the plug 3 when incorporated therewith. The plug is of predetermined thickness so as to snugly fit within the countersink of the 35 rim 2 with its inner face flush with the inner face of the skin of the container, and the upper face of the spud is provided with an annular bead 4 about the upper peripheral edge of its inclined exterior, said bead being 40 for the purpose of forming an annular seat about the bunghole through the spud when the skin of the container is forced into position thereabouts and into the inclined slot

5 about the bunghole. This seat is for the reception of the gasket 6 under the head 7 of the plug 8 which is screw threaded into the spud, the plug being of the ordinary type.

It is well known to those versed in the art that a gasket used under such plugs is very apt to become softened somewhat by the action of the contents of the barrel when kerosene or gasoline is contained therein, and under such circumstances the gasket is apt to bulge out in places by the compression of the plug, and it is obvious that the seat formed in the manner above described will prevent such bulging and render possible the repeated use of the gasket.

The slot 5 flares downwardly and outwardly in respect to the bunghole substantially parallel with the inclination of the outermost walls of the spud so that when the skin or shell of the receptacle is forced therein a clinching effect results which firmly secures the spud in position, as is obvious.

Having thus described my invention, what I claim and desire to secure by Letters Patent, is:

The combination with a metallic receptacle having a bunghole therein, of a spud for same having an inclined circumferential wall and an inclined annular slot spaced inwardly from the inclined wall and parallel therewith, said slot being for the reception of the marginal edges of the bunghole, and an annular stepped gasket seat intermediate of the uppermost termini of the inclined walls.

In testimony whereof I hereunto affix my signature in the presence of two witnesses.

THOMAS SEVERSON.
